John M. Martyn Jr.
Attys.

UNITED STATES PATENT OFFICE.

JOHN M. MARTY, JR., OF CLEVELAND, OHIO, ASSIGNOR OF ONE-HALF TO FREDERICK Z. MARTY, OF CLEVELAND, OHIO.

SIGNAL CONTAINER.

Application filed August 30, 1922. Serial No. 525,327.

To all whom it may concern:

Be it known that I, JOHN M. MARTY, Jr., a citizen of the United States, residing at Cleveland, in the county of Cuyahoga and

5 State of Ohio, have invented a certain new and useful Improvement in Signal Containers, of which the following is a full, clear, and exact description, reference being had to the accompanying drawings.

10 This invention is a carrier for rear end signals adapted to be attached to an automobile truck or other vehicle, and the object of the invention is to provide a simple and inexpensive device capable of carrying both 15 day and night signals in such manner that access can be quickly and easily had thereto when desired and a still further object is to provide a device of this character of such a nature that it can be attached to any of 20 the vehicles now in use at any convenient point.

In nearly all cities there are ordinances requiring a signal of some kind to be displayed at the end of any article projecting 25 rearwardly beyond the body of a vehicle.

This ordinance is usually complied with by tying a piece of red material to the projecting end of lumber or piece of pipe or other article and it frequently happens that 30 the driver of the truck is unable to find a suitable rear end signal inasmuch as no particular place has been provided for keeping such signals. Furthermore at night a visible signal is required and ordinarily a red 35 lamp is hung upon the projecting article. In most localities the ordinance requires the size of the signal to be displayed and very frequently this ordinance is violated for the reason that no particular place being pro- 40 vided for maintaining a signal the driver usually takes any red rag that may be convenient and attaches it to the end of the projecting article irrespective of the size or shape of said red rag.

45 It is the object of the present invention to avoid all of these objections by providing a casing which can be attached to the vehicle and which will hold a limited number of day-light signals of the proper size ready 50 for immediate attachment to the projecting end of the article and also a night signal which can be quickly and easily removed from the casing and applied to the projecting article.

55 The invention consists in certain details

of construction and in the manner of combining or arranging the same, all of which will be fully described hereinafter and pointed out in the claims.

In the drawings forming a part of this 60 specification Fig. 1 is a view showing the practical application of my invention, the day signal being displayed; Fig. 2 is a similar view with the night signal being displayed; and Fig. 3 is a sectional view of the 65 carrier, with the night and day signals enclosed therein. In carrying out my invention I employ a casing 10, preferably cylindrical in shape and of metal, though any suitable material may be employed. This 70 casing is of such length as to be capable of receiving both the day and night signals and is also of such diameter as to be capable of receiving a plurality of day signals. The day signal consists of a piece of fabric 11, 75 red in color and of the size and shape required by the ordinance and this fabric is connected to a suitable bail 12 provided with an eye 13 by means of which the attaching cord 14 can connect the signal to the projecting article 15 carried in the truck. In practice the casing or container is attached to the side of the truck or vehicle by means of suitable brackets 17, although it will be understood that the casing can be connected 80 at any point preferred. When not in use the day signal is rolled up and placed within the casing or container as most clearly shown in Fig. 3. The night signal 85 comprises an electric lamp 18 having red glass and the electric conductor 19 is projected through an insulated opening 20 produced in the side of the casing and connected with the lighting system of the automobile truck, in case the device is applied to an automobile truck. The day signals 11 are placed 90 in one end of the casing and the night signal 18 is placed in the other end of the casing and a partition 21 divides the casing into 95 two compartments. Each end is provided 100 with a cap 22 and each cap is connected to the casing by means of a chain 23. In order to prevent the cap jarring off when once placed upon the end of the casing I employ a 105 spring 24 which is placed upon the inner side of the casing and connected at its inner end by means of the rivet 25 to which one end of the chain 23 is attached and the outer end of this spring is turned laterally as 110 shown at 26 and projects slightly beyond the

110

edge of the casing and fits into an annular groove 27 produced in the cap 22. When the cap is applied to the end of the casing for the purpose of closing said end the spring 24 is forced back and when the cap is pushed to its final position this spring 24 will spring back so that the end 26 thereof will engage the groove 27 in the cap. This fastening means is sufficient to prevent the cap being jarred loose, but when it is desired to remove said cap it can be easily accomplished by giving a direct pull upon the same.

The casing or carrier provides a convenient place for carrying a number of day signals and one night signal and the operator of the truck or vehicle having a definite place to carry such articles will place them therein and consequently they will be available when needed. During the day the cap at one end will be removed, and a day signal taken from the carrier and applied to the projecting article and the cap replaced upon the end of the carrier. At night the cap is removed, the electric lamp and cable pulled therefrom at the end and applied to the projecting article. The electric cable being connected with the lighting system of the automobile a red light will be displayed upon a projecting merchandise. By having the caps connected to the casing by means of chains, all danger of misplacing the caps is avoided and by utilizing the same rivet for connecting the locking spring and the chains the construction of the device is simplified and the cost maintained at the lowest point.

It will thus be seen that I provide a simple, efficient and convenient form of carrier capable of connection to any of the vehicles now in use and providing proper compart-

ments for receiving the day and night signal and from which they can be quickly and easily removed when desired.

Having thus described my invention, what I claim is:

1. A device of the kind described comprising a casing open at each end and adapted to be attached to a vehicle, said casing having an intermediate partition dividing the same into two compartments, one compartment being adapted to receive a day signal and the other compartment a night signal, the side of said night signal compartment being apertured to permit the passage of an electrical cable, caps applied to the ends of the casing, spring tongues connected to the interior of the casing at each end and adapted to engage said caps to retain the same upon the ends of the casing.

2. A device of the kind described comprising a casing adapted to be attached to a vehicle, said casing being open at its opposite ends, a partition arranged in said casing, and dividing the same into two compartments, one of said compartments being adapted to receive a day signal and the other compartment a night signal, said night signal compartment having an aperture for the passage of an electric cable, caps applied to the ends of the casings, each cap having an interior annular groove, springs connected to the interior of the casing, each spring having an outwardly projecting bend adapted to engage the annular groove in the cap, rivets for connecting said springs to the casing and chains connected to said rivets at one end and to the caps at their other end.

In testimony whereof, I hereunto affix my signature.

JOHN M. MARTY, JR.
